(57) **ABSTRACT**

A paint gun for atomizing (in particular by way of compressed-air-assisted atomization) and applying a coating material such as a paint has a material-guiding part, a non-material-guiding part, and a transmitting and/or receiving device for wireless signal transmission. In order to increase the functional reliability and provide optimal operability in the environment in which the coating material is applied, the transmitting and/or receiving device for wireless signal transmission is arranged at a distance from the material-guiding part and is associated with the non-material-guiding part. Alternatively or additionally, an increased functional reliability is achieved by designing the transmitting and/or receiving device for wireless signal transmission in accordance with two different radio standards. Further-

(Continued)

more, a material application system comprising such a paint gun as well as a method for operating same are described.

**PAINT GUN, MATERIAL APPLICATION
SYSTEM, AND METHOD FOR OPERATING
SAME**

FIELD OF THE INVENTION

The invention relates to a paint spray gun for the atomization, in particular the compressed-air-assisted atomization, and application of a coating material, in particular a paint, wherein the paint spray gun has a material-conveying part with a material feed, a nozzle head and a material channel set-up, by means of which a coating material fed to the material feed can be supplied to the nozzle head, wherein the paint spray gun additionally has a non-material-conveying part and a transmitting and/or receiving device for wirelessly transmitting signals.

The invention also relates to a material application system having such a paint spray gun and to a method for operating a material application system.

BACKGROUND

A paint spray gun mentioned at the outset and a material application system having such a paint spray gun have been disclosed, for example, by WO 2012/052255 A1. In particular, said document describes a material application system in the form of a paint application system having one or more receiving units for wirelessly transmitting signals between components of the paint application system, wherein one of the components is a paint spray gun having a capture unit for capturing operating parameters of the paint spray gun and/or environmental parameters and having a transmitting unit for wirelessly transmitting the operating parameters and/or environmental parameters to the receiving unit.

SUMMARY

One aspect of the present invention relates to further developing the known paint spray gun and the known material application system in such a manner that the result is a paint spray gun and a material application system distinguished by increased functional reliability and user-friendliness which is optimized for use in paint spray booths.

The paint spray gun according to the invention is used to atomize and apply a coating material, in particular a liquid coating material. It has a material-conveying part with a material feed, a nozzle head and a material channel set-up, by means of which a (liquid) coating material fed to the material feed can be supplied to the nozzle head. The material-conveying part of the paint spray gun is preferably of multipart design. In particular, it is in the form of a separate interchangeable part into which the material channel set-up opens.

The material channel set-up and the material feed are formed, for example, inseparably from a common component, in particular a base body of the paint spray gun or the material-conveying part of the base body.

The paint spray gun additionally has a non-material-conveying part which is formed, for example, by a different part of the base body than the material-conveying part. The non-material-conveying part may preferably also be in the form of a component which is separate from the material-conveying part of the paint spray gun. Alternatively or additionally, the non-material-conveying part may be provided as a handling part. For this purpose, it may have

connection means for handling apparatuses, such as handling robots, and/or a handle or gripping elements for a painter.

Increased functional reliability is achieved by means of the paint spray gun according to the invention by virtue of the paint spray gun having a transmitting and/or receiving device for wirelessly transmitting signals which is at a distance from the material-conveying part and is associated with the non-material-conveying part. The transmitting and/or receiving device is consequently not integrated in the material-conveying part and is not arranged in a manner immediately adjacent to the material-conveying part.

The arrangement of the transmitting and/or receiving device substantially reduces the risk of the coating material being applied to the transmitting and/or receiving device and therefore substantially reduces damage or impairment of the transmitting and/or receiving device.

The coating materials conventionally used with a paint spray gun, such as paints in particular, make it necessary to carefully clean the material-conveying part of the paint spray gun, both mechanically and using solvents. The arrangement according to the invention of the transmitting and/or receiving device reduces the risk of damage or impairment of the transmitting and/or receiving device when cleaning the paint spray gun.

In the case of one preferred exemplary embodiment, the transmitting and/or receiving device is arranged in or on the non-material-conveying part, in particular is integrated and/or encapsulated in the non-material-conveying part.

The paint spray gun according to the invention is preferably a flow cup spray gun, that is to say the material feed has a connection device for a flow cup. Alternatively or additionally, the paint spray gun may also be in the form of a paint spray gun with pressure-assisted material feed (for example a boiler or robot spray gun) or may have a material feed which is suitable for connecting a material hose.

The transmitting and/or receiving device is preferably suitable for bidirectionally wireless data transmission. This is consequently a transmitting and receiving device in this case.

Explosive gas mixtures may arise during painting. Therefore, strict explosion protection requirements apply, in particular in paint spray booths and for all devices used there. The transmitting and/or receiving device is therefore preferably configured such that these requirements are met. In particular, this is effected by means of appropriate encapsulation and/or an appropriate structure of the electronic components.

One exemplary embodiment of the invention, in which the paint spray gun is in the form of a handheld paint spray gun, is particularly relevant in practice. The non-material-conveying part is preferably in the form of a handling part. The non-material-conveying part has a handle, for example, in which case an actuation lever of the paint spray gun is preferably articulated to the material-conveying part.

However, the paint spray gun may also be actuated, for example, by means of a compressed air valve which is actuated manually or via an external control connection.

In one preferred exemplary embodiment, the paint spray gun is provided with a compressed air connection, from which a compressed air channel system leads to the material application nozzle. It is consequently, in particular, a paint spray gun which atomizes the coating material in a compressed-air-assisted manner. It is preferably a HVLP paint spray gun or a compliant paint spray gun or a paint spray gun which may be in the form of a HVLP or compliant paint spray gun depending on the choice of the nozzle head.

One variant in which the compressed air connection is arranged on the non-material-conveying part has proved itself. The compressed air is preferably guided, via the non-material-conveying part, to the material-conveying part and from there to the nozzle head, where the compressed air is used to atomize the coating material (atomization compressed air) and/or to form the spray jet (for example horn compressed air).

According to one particularly preferred exemplary embodiment, in addition to the transmitting and/or receiving device, the paint spray gun comprises one or more electronic components which are directly or indirectly connected to the transmitting and/or receiving unit. Examples which can be mentioned are one or more sensor units, one or more actuator units, one or more display units, a data storage unit, a data processing unit and/or an energy storage unit.

One variant is distinguished by simple incorporation in a modular standardized network, in which variant one or more sensor units of the paint spray gun are provided in a semiconductor design, use the standard protocol MQTT to transmit sensor values and have the hardware interface I²C.

By way of example, one or more sensor units for measuring the material, atomization or nozzle internal pressure, the air pressure in the horn compressed air region or the transport air pressure are provided. Furthermore, a sensor unit for measuring the material or compressed air flow rate may be advantageous. Furthermore, a paint spray gun may preferably be provided with a sensor unit which detects actuation of an actuation lever (discharge) or a sensor unit for determining the gun position and/or movement.

However, in addition to sensor units for determining operating parameters of the paint spray gun, one or more sensor units for determining environmental parameters, for example the air pressure, the humidity, the air speed and/or the ambient temperature, may also be advantageously provided on the paint spray gun.

In particular, the sensor units for determining environmental parameters may also be provided separately from the paint spray gun in connection with another module of a network, in which the paint spray gun is incorporated.

One or more controllable actuator units are preferably provided on the paint spray gun. In the case of one particularly preferred exemplary embodiment, the paint spray gun has one or more actuator units in the form of a pressure control valve which are directly or indirectly connected to the transmitting and/or receiving device.

In one advantageous variant of the invention, a sensor unit for measuring the atomization air pressure and an actuator unit in the form of a pressure control valve for adjusting the atomization pressure are provided, for example, on the paint spray gun. Overall, a control loop for the pressure of the atomization compressed air is formed in the paint spray gun and can be used to measure the pressure directly at the paint spray gun and to control it to a desired target value. This is particularly advantageous in the case of paint spray guns for liquid paints in particular, since the paint application quality decisively depends on the atomization and therefore on the atomization pressure directly applied to the nozzle head. Alternatively or additionally, a control loop may also be provided for another setting parameter, for example the pressure of the horn compressed air. If appropriate, three or more control loops may also be provided for further setting parameters.

In the case of one particularly preferred exemplary embodiment, the paint spray gun has a display unit which is directly or indirectly connected to the transmitting and/or receiving device and displays the following information, for

example: measured sensor values from sensor units of the paint spray gun or from other modules; target values for setting and/or operating parameters; optical warning or alarm signals, data relating to the coating material or the current coating task etc.

Alternatively or additionally, the paint spray gun may be provided with a haptic or acoustic warning or alarm function (for example vibration alarm).

The stated information and further information may also be displayed, for example, on a display unit in connection with another module of a network, in which the paint spray gun is incorporated.

The paint spray gun preferably also has a data processing unit (CPU) for controlling the transmitting and/or receiving device, the sensor and/or actuator units and for processing data from these units.

In one particularly preferred exemplary embodiment, an energy storage unit is provided and can be charged in a contactless manner, in particular.

The paint spray gun may preferably be additionally provided with a USB interface which is directly or indirectly connected to one or more of the electronic components or the transmitting and/or receiving device.

The electronic components are preferably likewise at a distance from the material-conveying part and associated with the non-material-conveying part.

In the case of one advantageous variant, the transmitting and/or receiving unit and one or more of the electronic components are in the form of an electronic module. In particular, the electronic module comprises a circuit board on which some of the components are arranged. The electronic components are preferably in the form of SMD components which are arranged on an SMD circuit board, thus resulting in a space-saving and cost-effective design of the electronic module.

In one particularly preferred exemplary embodiment, the transmitting and/or receiving device is releasably connected to the paint spray gun. The transmitting and/or receiving device can be removed, for example, before cleaning the paint spray gun and can then be connected to the cleaned paint spray gun again. This prevents damage during the cleaning operation. The cleaning of the remaining part, in particular the material-conveying part, is simplified since no consideration must be given to the transmitting and/or receiving device.

The transmitting and/or receiving device is preferably part of a removable electronic module having one or more further electronic components, which electronic module is integrated in the handle of the paint spray gun, for example. The transmitting and/or receiving device or the electronic module may also be integrated in a handle of the paint spray gun, which handle can be removed overall as a unit from the remaining paint spray gun, in particular the material-conveying part of the paint spray gun.

One variant of the paint spray gun is distinguished by a particularly advantageous air pressure measurement, in which variant at least one pressure measuring channel is provided and is routed from a compressed air chamber in the material-conveying part of the paint spray gun to an electronic component in the form of a pressure sensor, wherein the pressure sensor is at a distance from the material-conveying part and is associated with the non-material-conveying part. In particular, the pressure sensor belongs to an electronic module having the features explained above.

The pressure measuring channel is preferably formed, at least in sections, by a bore or a channel in the material-conveying part and/or in the non-material-conveying part of

the paint spray gun. Alternatively or additionally, a pressure measuring channel may also be formed by a hose or the like.

In one particularly preferred exemplary embodiment, the paint spray gun has a round/broad jet setting device which is used to variably divide supplied compressed air into atomization compressed air and horn compressed air which are each supplied to the nozzle head. At least one atomization compressed air region and one horn compressed air region result downstream of the round/broad jet setting device.

The compressed air chamber, from which a pressure measuring channel is routed to a pressure sensor, is preferably formed by the atomization compressed air region or is arranged in the atomization compressed air region. Alternatively or additionally, a (further) compressed air chamber, from which a (further) pressure measuring channel is routed to a (further) pressure sensor, is formed by the horn compressed air region.

In one advantageous further development, one or more pressure chambers, from which a pressure measuring channel is routed to a pressure sensor, directly adjoining the exchangeable nozzle head. This compressed air chamber or these compressed air chambers is/are preferably arranged in the atomization compressed air region and/or horn air region.

Increased functional reliability is also achieved by means of a paint spray gun in which a transmitting and/or receiving device is designed to wirelessly transmit signals according to a first radio standard, for example Bluetooth, and is additionally designed to wirelessly transmit signals according to a second radio standard, for example LoRawan, wherein the second radio standard is suitable for wirelessly transmitting signals over a wider range than the first radio standard, and in particular also through the walls of paint spray booths. In this sense, the second radio standard is, for example, a radio standard which is distinguished by a wider free field range than the first radio standard. In particular, the second radio standard is distinguished by a wider range in the paint spray environment. It has a greater penetration of paint spray booth walls and similar obstacles.

In particular, Bluetooth LE 5.0 has proved itself in practice as the first radio standard and LoRawan at 433/866 MHz or 910 MHz has proved itself as the second radio standard. Further possible radio standards are, for example, WLAN, DECT ULE, EnOcean, ZigBee or Z-wave.

A reliable transmitting or receiving power is ensured by virtue of the transmitting and/or receiving device respectively having an antenna for transmitting signals for each of the different radio standards in one preferred exemplary embodiment.

The invention also relates to a material application system having a paint spray gun with the features explained above and below, wherein the material application system has at least one module which is separate from the paint spray gun and comprises a transmitting and/or receiving device for wirelessly transmitting signals from and to the transmitting and/or receiving device of the paint spray gun.

The material application system preferably forms a modular ATEX-approved network for capturing and processing relevant parameters at all conceivable points of the paint spraying process. The aim of processing the information from a plurality of modules networked in this manner in a central unit is also expanded planning possibilities (preventative maintenance, capture of operating and consumption data, capture of the need to exchange worn parts etc.). Incorporating paint spray guns and further products involved in the paint spraying process makes it possible to determine,

transmit and evaluate a multiplicity of different items of information and data (for example filter saturation state, pressure values from filters, gun setting, material pressure, throughputs of air or/and material, temperatures of materials and the environment, humidity, operating times of guns, consumption values for material and/or compressed air, state of charge, time, summation of the operating time, etc.).

A wirelessly networked material application system advantageously matched to the occurrences of paint spraying processes results by virtue of the material application system having at least two modules which are separate from the paint spray gun and each comprise a transmitting and/or receiving device for wirelessly transmitting signals from and to the transmitting and/or receiving device of the paint spray gun.

In this case, one of the modules is a near field module, in particular a portable near field module, for use in a paint spray booth and for transmitting signals from and to the transmitting and/or receiving device according to a first radio standard.

Alternatively or additionally, another of the modules is in the form of a region module, in particular a stationary region module, for use outside a paint spray booth for transmitting signals from and to the transmitting and/or receiving device according to a second radio standard.

It goes without saying that the second radio standard is suitable for transmitting signals over a wider range than the first radio standard; in particular, the second radio standard is suitable for transmitting signals from inside a paint spray booth, through a booth wall, to the outside or vice versa.

Preferred examples of the configuration of the near field module which can be mentioned are a wristwatch, a wall clock, a tablet, data glasses, a smartphone, a data logger or the like. A near field module could possibly also be in the form of an ATEX-compliant notebook. However, standard notebooks are not ATEX-compliant.

The design of the near field module as a wristwatch is particularly preferred. For example, the wristwatch can be used to display pressure values. The watch preferably makes it possible to input target values for setting parameters of the paint spray gun. The watch may provide acoustic, optical or haptic (vibration) alarm or warning functions.

The region module is characterized, in particular, in that it is suitable for incorporation in a central network (possibly with an Internet interface). In particular, it is suitable for connection to a data processing system, for example a PC. In this manner, all functions of the PC can also be used for the network of the material application system, such as storage, processing, input or forwarding of data, in particular also to connected networks (wirelessly, by cable, by USB, by mail, by SMS, etc.). For example, the climate data currently available at the place of use can also be obtained via the Internet and can be taken into account.

The transmitting and/or receiving device of the region module may preferably additionally be designed to transmit signals according to the first radio standard. This makes it possible for the region module to communicate with further modules of the network which are in the vicinity of the region module. In particular, the region module may communicate with one or more near field modules if they come into the vicinity of the region module, for example from the paint spray booth.

The invention also relates to a method for operating a material application system, in which information relating to proposals for setting parameters or other operating parameters of the paint spray gun for a coating task and/or measured values of setting parameters or other operating

parameters of a coating task carried out with the paint spray gun is transmitted by transmitting signals between the transmitting and/or receiving device of the paint spray gun and the transmitting and/or receiving device of the separate module or the transmitting and/or receiving devices of the separate modules. A proposal for a nozzle type to be used (HVLP, compliant etc.) or the nozzle size can also be mentioned as information to be transmitted, for example.

In the case of one particularly preferred example, proposals for setting parameters or other operating parameters of the coating task with the paint spray gun are automatically determined on the basis of an identification of the coating material, for example by means of a barcode reader, for a pending coating task with the paint spray gun and preferably on the basis of further operating and/or environmental parameters. The proposals are transmitted from the separate module or from the separate modules to the paint spray gun and/or vice versa by means of the transmitting and/or receiving devices.

BRIEF DESCRIPTION OF THE DRAWINGS

The invention is explained below on the basis of exemplary embodiments. In the figures:

FIG. 1 shows a paint spray gun having a removable electronic module which comprises a transmitting and/or receiving unit,

FIG. 2 shows a sectional illustration of the front section of the paint spray gun according to FIG. 1,

FIG. 3 shows the schematic structure of a wirelessly networked material application system having two paint spray guns according to FIG. 1.

DETAILED DESCRIPTION

FIG. 1 shows a handheld paint spray gun 1 for the compressed-air-assisted atomization and application of a coating material. The paint spray gun 1 is in the form of a HVLP paint spray gun. Alternatively, it could also be in the form of a compliant paint spray gun.

The paint spray gun 1 comprises a base body 2 having a material-conveying part 3 and a non-material-conveying part 4 which is in the form of a handling part with a handle 5 for a painter. An actuation lever 6 is pivotably fitted to the material-conveying part 3. A compressed air connection 7, for example for a compressed air supply hose which is not shown, is provided at the lower end of the handle 5. Starting from the compressed air connection 7, supplied compressed air is guided, by means of a compressed air line system inside the paint spray gun, to a nozzle head 9 of the paint spray gun 1 via a round/broad jet setting device 8. The round/broad jet setting device 8 is used to set the division of the supplied compressed air into atomization compressed air and horn compressed air which are separately supplied to the nozzle head 9. At least one atomization compressed air region 10 and one horn compressed air region 11 (FIG. 2) are therefore formed in the material-conveying part 3 of the paint spray gun 1 downstream of the round/broad jet setting device 8.

The material-conveying part 3 has a material feed 12 in the form of a flow cup connection. The material-conveying part 3 of the paint spray gun 1 is also provided with the interchangeable nozzle head 9. Under the influence of gravity and on account of a suction effect of the atomization air emerging at the nozzle head 9, the coating material, for example paint, is conveyed, via a material channel set-up 13

(FIG. 2), from a flow cup connected to the flow cup connection to the nozzle head 9.

The paint spray gun 1 also has an electronic module 14 integrated in the handle 5. The electronic module 14 is removable, with the result that it can be temporarily removed, for example for cleaning the paint spray gun 1 with solvent. In an alternative configuration, the entire handle 5 can also be removable as a unit from the upper part of the paint spray gun 1 which comprises the material-conveying part 3. In both cases, the electronic module 14 is at a distance from the material-conveying part 3 of the paint spray gun 1 and is associated with the non-material-conveying part 4.

The electronic module 14 comprises, inter alia, a transmitting and/or receiving device 15 for wirelessly transmitting signals, which device is indicated in FIG. 1. The transmitting and/or receiving device 15 is designed to wirelessly transmit signals according to two different radio standards. Bluetooth LE 5.0 is used as the first radio standard. LoRaWan at 433/866 MHz or 910 MHz is used as the second radio standard. The second radio standard is suitable for wirelessly transmitting signals over a wider range than the first radio standard and through obstacles which may be present (for example the wall of a paint spray booth). The transmitting and/or receiving device 15 is respectively provided with an antenna accommodated in the paint spray gun 1 for each of the two radio standards.

In addition to the transmitting and/or receiving device 15, the electronic module 14 has a plurality of electronic components which are directly or indirectly connected to the transmitting and/or receiving unit 15. The electronic module 14 therefore comprises two pressure sensor units, a data storage unit, a data processing unit (CPU) and an energy storage unit in the form of a contactlessly rechargeable battery. The charging coil 16 of the battery is indicated in FIG. 1.

The electronic module 14 comprises a circuit board to which, inter alia, the pressure sensor units in the form of SMD components, a data storage unit and the data processing unit (CPU) are applied. The components, in particular the sensors, need not be directly arranged on the circuit board, but rather may also be separated from the circuit board and may be connected to the circuit board or to components on the circuit board or to other components or units separated from the circuit board in a wired or wireless manner.

As already explained above, in another exemplary embodiment, other or additional electronic components, such as an actuator unit and a display unit etc., may be provided.

The pressure sensor units or pressure sensors are used to measure the air pressure in two different pressure chambers 17, 18 in the material-conveying part 3 of the paint spray gun 1. The pressure chambers 17, 18, from each of which a pressure measuring channel 19, 20 is routed to one of the pressure sensors, are shown in FIG. 2 in which the front section of the paint spray gun 1 is illustrated in section.

The interchangeable nozzle head 9 is screwed onto a front section of the base body 2 of the paint spray gun 1. FIG. 2 shows a section of the material channel set-up 13 which opens into the nozzle head 9. The nozzle head 9 comprises a screwed-in material nozzle 21 surrounded by an air nozzle arrangement 22 which forms an outlet gap 23 for the atomization air and is provided with two opposite horns 24 with horn air nozzles 25. The air nozzle arrangement 22 is interchangeably fastened to the base body 2 of the paint spray gun 1 by means of an air nozzle ring 26. A baffle disk

27 is permanently connected to the material nozzle 21 and is concomitantly removed when disassembling the nozzle head 9.

It is clear from FIG. 2 that the first compressed air chamber 17 is formed by the atomization compressed air region 10 or is arranged in the atomization compressed air region 10. The second compressed air chamber 18 is formed by the horn compressed air region 11 or is arranged in the horn compressed air region 11. Both compressed air chambers 17, 18 directly adjoin the nozzle head 9, that is to say part of the wall of the pressure chambers 17, 18 is formed by the nozzle head 9.

The pressure measuring channels 19, 20 indicated in FIG. 2 are formed in the material-conveying part 3 and in the non-material-conveying part 4 of the paint spray gun 1 as a bore and open in the electronic module 14.

There is a precise pressure measurement of the atomization compressed air and of the horn compressed area in the immediate vicinity of the atomization process. However, the pressure sensors are accommodated at a distance from the material-conveying part 3 of the paint spray gun 1 and therefore in a well-protected manner in the electronic module 14 which is arranged on the handle 5. The measured values from the pressure sensors can be stored, for example, by the data storage unit, can be processed by the data processing unit and can be transmitted to another module of the material application system 28 by means of the transmitting and/or receiving device 15.

An exemplary structure of the material application system 28 is explained on the basis of FIG. 3.

The material application system 28 has, for example, two paint spray guns 1 according to FIG. 1 which are each provided with an electronic module 14. A portable near field module 30 is also provided inside a paint spray booth 29 and is in the form of a wristwatch. The wristwatch can be worn by a painter working with the two paint spray guns 1. The wristwatch is suitable for bidirectionally transmitting signals with the paint spray guns 1 with the aid of the Bluetooth LE 5.0 radio standard. It has a display which can be used to display different items of data and information. For example, the pressure values measured by the pressure sensors in the paint spray guns 1 can be displayed. The watch also makes it possible to input target values, for example for the measured pressures, and provides an acoustic, optical or haptic (vibration) alarm or warning function if the measured actual value differs (too greatly) from a predefined target value.

It goes without saying that further paint spray guns 1 or further near field modules 30, which may have a different design to the wristwatch, can be incorporated in the modular and standardized network of the material application system 28.

A stationary region module 31 (gateway) is arranged outside the paint spray booth and is suitable for bidirectionally transmitting signals with the two paint spray guns 1 according to the LoRawan radio standard. The region module 31 has Internet capability, for example, has a powerful CPU and a display. It is connected to a PC 32 on which it is possible to install different software applications which evaluate data transmitted by the paint spray guns 1 and generate data for transmission to the paint spray guns 1.

The region module 31 may also be connected to a mobile telephone 33, a tablet etc., on which it is likewise possible to install different software applications which evaluate data transmitted by the paint spray guns 1 and generate data for transmission to the paint spray guns 1. The bidirectional signal transmission between the mobile telephone 33 etc.

and the region module 31 is carried out according to the first radio standard (Bluetooth). If the near field module 30 comes into the vicinity of the region module 31 from the paint spray booth 29, it can also receive data/information from the region module 31 or can transmit data/information to the latter according to the first radio standard (Bluetooth).

During operation of the material application system 28, information relating to proposals for setting parameters or other operating parameters of the paint spray gun 1 for a coating task and/or measured values of setting parameters or other operating parameters of a coating task carried out with the paint spray gun 1 is transmitted between the transmitting and/or receiving device 15 of the paint spray guns 1, the near field module and the region module.

In particular, a paint for a pending car paint repair job, for example, can be first of all identified by means of a barcode reader which is connected to the network. A software application installed on the PC 32 reads the information from a data sheet for the paint which is stored in a database. On the basis of the information in the data sheet and taking into account currently measured environmental parameters in the paint spray booth 29, for example, proposals for the nozzle selection and (target values) for the pressure of the atomization compressed air or the horn compressed air are determined. The proposals (target values) are transmitted to the paint spray gun(s) 1 and are possibly transmitted from there on to the wristband watch for display.

The described paint spray gun, the described material application system and the described method for operating a material application system can be used, in particular, in the industrial sector, that is to say it can be integrated in non-handheld automatic or robot paint spray guns or can be used therefor. It is also possible to incorporate components in already existing networks (Industry 4.0, digitization), for example in in-house networks, in order to make it possible to interchange data between different departments or different hierarchies. Alternatively or additionally, it may be possible to incorporate components in a network with a connection to a device outside one's own company in order to make it possible to interchange data with other companies, authorities or other devices or persons. These may be, for example, suppliers, customers, partners, supervisory bodies. In particular, data from a paint spraying company can be sent to a supplier of paint, paint spray tools, in particular paint spray guns, or spare parts, in particular nozzle sets for paint spray guns or cartridges for filters, in order to enable preventative maintenance or the delivery of a spare part on the basis of the captured operating data. However, provision may also be made for data to be transmitted to a customer, with the result that the latter can track the status of his paint spray order. The components can be incorporated, for example, via LAN, WLAN or other wired or wireless transmission technologies.

The invention claimed is:

1. A paint spray gun for atomization and application of a paint, the paint spray gun comprising:
  - a material-conveying portion into which a material channel system opens, the material-conveying portion including:
    - a material feed configured for receiving the paint;
    - a nozzle head; and
    - the material channel system which leads to the nozzle, the material channel system being configured for conveying the paint from the material feed to the nozzle head;

11

a non-material-conveying portion of the paint spray gun; a transmitting and receiving device configured for bidirectional wireless data transmission; and a compressed air connection and a compressed air line system, the compressed air line system being configured for guiding compressed air from the compressed air connection to the nozzle head, wherein the transmitting and receiving device is at a distance from the material-conveying portion and is associated with the non-material-conveying portion, wherein the transmitting and receiving device is configured for wireless data transmission according to a first radio standard, and is additionally configured for wireless data transmission according to a second radio standard, wherein the second radio standard is suitable for wirelessly transmitting data over a wider range than the first radio standard, wherein the paint spray gun further comprises a first pressure measuring channel that is routed from a first compressed air chamber in the material-conveying portion of the paint spray gun to a first pressure sensor, the first pressure measuring channel being different than the compressed air line system that guides compressed air from the compressed air connection to the nozzle head, wherein the first compressed air chamber is formed by or arranged in an atomization compressed air region in the material-conveying portion of the paint spray gun, and the first pressure sensor is configured to measure air pressure in the atomization compressed air region, and wherein the first pressure sensor is at a distance from the material-conveying portion and is associated with the non-material-conveying portion.

2. The paint spray gun as claimed in claim 1, wherein the paint spray gun is in the form of a handheld paint spray gun.

3. The paint spray gun as claimed in claim 1, wherein the paint spray gun includes an electronic module that includes the transmitting and receiving device and one or more of the following electronic components which are directly or indirectly connected to the transmitting and receiving device: one or more actuator units, a display unit, or a CPU, and wherein the electronic module is at a distance from the material-conveying portion and is associated with the non-material-conveying portion, and is configured to be removable as a unit from the paint spray gun so as to be capable of being removed for cleaning the paint spray gun.

4. A paint application system comprising: the paint spray gun as claimed in claim 1; and at least one module which is separate from the paint spray gun and comprises a transmitting and receiving device configured for bidirectional wireless data transmission with the transmitting and receiving device of the paint spray gun.

5. The paint application system as claimed in claim 4, wherein the paint application system comprises at least two modules which are separate from the paint spray gun and each comprise a transmitting and receiving device configured for bidirectional wireless data transmission with the transmitting and receiving device of the paint spray gun,

wherein one of the modules is in the form of a near field module for use in a paint spray booth and is configured for wireless data transmission with the transmitting and receiving device of the paint spray gun according to the

12

first radio standard, and another of the modules is in the form of a gateway for use outside the paint spray booth and is configured for wireless data transmission with the transmitting and receiving device of the paint spray gun according to the second radio standard, and

wherein the second radio standard is suitable for wirelessly transmitting data from inside the paint spray booth, through a wall of the paint spray booth, to the outside, and vice versa.

10. The paint application system as claimed in claim 4, wherein the transmitting and receiving device of the paint spray gun is configured for wirelessly transmitting data relating to proposals for setting parameters or other operating parameters of the paint spray gun for a coating task and/or measured values of setting parameters or other operating parameters of the coating task to and from the transmitting and receiving device of the at least one module.

15. The paint application system as claimed in claim 6, wherein the transmitting and receiving device of the at least one module is configured for determining the proposals for setting parameters or other operating parameters of the coating task on the basis of an identification of the paint for the coating task and on the basis of further operating and/or environmental parameters.

20. The paint spray gun as claimed in claim 1, wherein the compressed air connection is arranged on the non-material-conveying portion of the paint spray gun.

25. The paint spray gun as claimed in claim 1, wherein the first pressure measuring channel is formed, at least in part, by a bore that passes through both the material-conveying portion and the non-material-conveying portion of the paint spray gun, the bore not being part of the compressed air line system.

30. The paint spray gun as claimed in claim 1, wherein the first radio standard is a packet-based personal area network communication protocol that uses frequency hopping in the 2.4 GHz unlicensed radio band to interconnect devices, and the second radio standard is a wireless communication protocol, and wherein the paint spray gun includes an antenna for wirelessly transmitting data according to each of the two radio standards.

35. The paint application system as claimed in claim 5, wherein the near field module is a portable near field module and the gateway is a stationary gateway.

40. The paint application system as claimed in claim 7, wherein the proposals for setting parameters or other operating parameters of the coating task are automatically determined, and wherein the identification of the paint is determined via a barcode reader.

45. The paint spray gun as claimed in claim 1, further comprising:

50. a handle for a painter, wherein the transmitting and receiving device is integrated in the handle of the paint spray gun, and wherein the handle, into which the transmitting and receiving device is integrated, is configured to be removable as a unit from the paint spray gun so as to be capable of being removed for cleaning the paint spray gun.

55. The paint spray gun as claimed in claim 1, further comprising: an electronic module that includes the first pressure sensor and the transmitting and receiving device, wherein the electronic module, which includes the first pressure sensor and the transmitting and receiving

device, is configured to be removable as a unit from the paint spray gun so as to be capable of being removed for cleaning the paint spray gun.

15. The paint spray gun as claimed in claim 1, further comprising:

a second pressure measuring channel that is routed from a second compressed air chamber in the material-conveying portion of the paint spray gun to a second pressure sensor, the second pressure measuring channel being different than the compressed air line system that guides compressed air from the compressed air connection to the nozzle head,

wherein the second compressed air chamber is formed by or arranged in a horn compressed air region in the material-conveying portion of the paint spray gun, and the second pressure sensor is configured to measure air pressure in the horn compressed air region, and wherein the second pressure sensor is at a distance from the material-conveying portion and is associated with the non-material-conveying portion.
